(57) **CLAIM**

The ornamental design for a combined container and removable bins, as shown and described.

DESCRIPTION

FIG. 1 is a perspective view of a container according to the present invention;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the container according to FIG. 1 containing a first set of eight identical removable bins according to the present invention;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a first perspective view of one of the eight identical removable bins shown within the container in FIG. 8, separated from the container to more clearly show the bin's appearance, showing parts thereof in a closed state;

FIG. 16 is a second perspective view thereof, showing parts thereof in an open state;

FIG. 17 is a front view thereof;

FIG. 18 is a rear view thereof;

FIG. 19 is a left side view thereof;

FIG. 20 is a right side view thereof;

FIG. 21 is a top view thereof; and,

FIG. 22 is a bottom view thereof.

The broken lines depict portions of the container that form no part of the claimed design.
